US0D1103963S

(12) **United States Design Patent** (10) **Patent No.:** **US D1,103,963 S**
(45) **Date of Patent:** **** Dec. 2, 2025**

(54) **COMBINED SPEAKER AND CHARGING CRADLE**

(71) Applicant: **Shenzhen Hongtian Electronics Co., Ltd.**, Guangdong (CN)

(72) Inventor: **Quanhua Zhang**, Guangdong (CN)

(**) Term: **15 Years**

(21) Appl. No.: **29/953,861**

(22) Filed: **Jul. 24, 2024**

(51) **LOC (15) Cl. 14-01**

(52) **U.S. Cl.**

USPC **D14/209.1**

(58) **Field of Classification Search**

USPC D14/204, 210, 216, 209.1

CPC .. H04R 1/025; H04R 2205/021; F16M 13/02;

F16M 13/04; F16M 13/005

(57) **CLAIM**

The ornamental design for a combined speaker and charging cradle, as shown and described.

DESCRIPTION

FIG. 1 is a perspective view of a combined speaker and charging cradle showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear, left, bottom perspective view thereof; and, FIG. 9 is a front perspective view thereof, shown a separated state.

The broken lines in the drawings depict portions of the combined speaker and charging cradle that form no part of the claimed design.

1 Claim, 9 Drawing Sheets
